(57) **CLAIM**

The ornamental design for a grinding machine, as shown and described.

DESCRIPTION

FIG. 1 is a front, top, and right side perspective view of a grinding machine showing the new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a front, top, and right side perspective view of the grinding machine in a use position.

FIG. 8 is a front elevational view thereof.

FIG. 9 is a left side elevational view thereof.

FIG. 10 is a right side elevational view thereof; and,

FIG. 11 is a top plan view thereof.

The broken lines shown in the figures are for the purpose of illustrating portions of the grinding machine that form no part of the claim.

1 Claim, 11 Drawing Sheets
